UNITED STATES PATENT OFFICE.

ERNST LAUSCHKE, OF CHICAGO, ILLINOIS, ASSIGNOR TO BARNHART BROS.
& SPINDLER, OF SAME PLACE.

DESIGN FOR A FONT OF PRINTING-TYPE.

SPECIFICATION forming part of Design No. 17,801, dated October 18, 1887.

Application filed August 8, 1887. Serial No. 246,469. Term of patent 7 years.

To all whom it may concern:

Be it known that I, ERNST LAUSCHKE, a subject of the Emperor of Germany, residing at Chicago, in the county of Cook and State 5 of Illinois, have invented and produced a new and original Design for a Font of Printing-Type, which is fully described in the following specification, reference being had to the accompanying typographic impressions, which 10 are exact representations of said design.

The character of this design is a moderately heavy, quite condensed, and somewhat ornamental type; and it comprises capitals, lower-case letters, character & and dollar-mark, (§,) 15 figures, and points.

The letters, except their ornamentation, are composed of medium broad uniform-width lines, without shade-lines and with very slight ceriphs. The ornamentation consists in fine 20 lines drooping from the ends of horizontal lines and terminating in a dot or bead, and in the prolongation of curves and cross-lines across the stems or vertical lines, such prolongations being curves drooping downward and

tapering to a point. The first-mentioned ornamentation is seen in capitals G, E, S, and others, the second in capitals P, R, K, and B.

The lower-case letters have analogous ornamentation, the fine line terminating a dot appearing in the cross of t, the flourish from the top of h, the tail of the g, and elsewhere, and the tapering curve being presented in the lower terminals of n, t, h, and other letters.

I claim—

The design for a font of printing-type herein 35 shown and described, in which the letters are of medium broad-faced lines of uniform width, without shade-lines and with very slight acutely-pointed ceriphs, are quite condensed, and have ornamentation consisting of drooping fine lines terminating in dots and tapering curve lines ending in points, substantially 40 as illustrated.

ERNST LAUSCHKE.
